UNITED STATES PATENT OFFICE.

JOHN F. BANTA, OF GOSHEN, INDIANA.

BED-FRAME CORNER CONSTRUCTION.

1,211,908.

Specification of Letters Patent.

Patented Jan. 9, 1917.

Application filed August 23, 1915. Serial No. 46,779.

To all whom it may concern:

Be it known that I, JOHN F. BANTA, a citizen of the United States of America, and resident of 223 South Third street, Goshen, Indiana, where I am now living and receive mail, have invented a certain new and useful Improvement in Bed-Frame Corner Constructions, of which the following is a specification.

10 My invention relates to devices for coupling the side rails to the corner posts of bed frames.

More specifically considered, it relates to bed frames in which the said corner posts 15 are of wood, while the side rails are of angle iron formation.

The object of my invention is to provide a simple and reliable coupling for this purpose, which will be economical to manufacture, and which will be convenient and 20 easy to operate, as will hereinafter more fully appear.

It is also an object to provide an improved construction and arrangement involving the use of sheet metal for the different parts of the coupling, thus avoiding the use of castings, as will also hereinafter 25 more fully appear.

To the foregoing and other useful ends 30 my invention consists in matters hereinafter set forth and claimed.

In the accompanying drawings Figure 1 is a vertical section on line 1—1 in Fig. 2, showing a bed frame corner construction or 35 coupling involving the principles of my invention. Fig. 2 is a vertical section on line 2—2 in Fig. 1. Fig. 3 is a horizontal section on line 3—3 in Fig. 2. Fig. 4 is a perspective of the portion of the bed post to which 40 the bracket plate of the coupling is secured. Fig. 5 is a view of the sheet metal blank from which the trough-shaped side rail coupling member is formed.

As thus illustrated, my invention comprises a wood post A of any suitable character, there being one of these at each corner of the bed frame, as will be readily understood. The side rails B of the said frame are of angle iron formation, the vertical 45 web 1 being on the outside of the frame, and the horizontal flange 2 forming the top of the rail. A sheet metal bracket plate C is secured by screws c to the face of the post A, and is provided with edge portions 3 50 which are cut away and bent inward toward

each other to form upturned lugs or hooks. It will be observed that these lugs or hooks 3 are disposed in parallel vertical planes which are also parallel with the side rail, it being also observed that these hooks are 50 arranged in pairs above and below the side rail. The coupling member D is trough-shaped, as shown in Fig. 3, and has its vertical wall d provided with upper and lower slots 4 which receive the hooks 3, in the 55 manner shown, and whereby the plate C and the vertical wall d are held flatwise together. The member D is provided with parallel side walls 5 and 6, it being observed that the wall 5 is secured by rivets x to the 60 web 1 of the angle iron side rail. The wall 6 has a portion 7 thereof cut away and bent 65 inward to rest horizontally upon the top of the side rail, this horizontal web 7 forming a shoulder which is secured by a rivet 8 to the 70 flange or top of the angle iron side rail. Thus both side walls of the coupling member 75 D are secured to the end of the side rail, but as the latter is of angle iron formation one of said walls has a portion thereof 80 cut away and bent inward to rest, as stated, upon the top of the side rail. By raising the side rail, in a manner that will be readily understood, the slots 4 can be readily disengaged from the hooks 3, thereby disconnecting the side rail from the post. In 85 setting up the bed frame, the coupling member D is presented in vertical position to the bracket plate C, and with the slots 4 opposite the hooks 3, and the relative formation 90 is such that the said coupling member then readily settles into position with the upper ends of said slots resting firmly in the throats of said hooks. Preferably, as shown, the lower edges of the hooks 3 are beveled 95 or inclined to operate as cams for deflecting or inclined to operate as cams for deflecting the lower ends of said slots outward when the side rail is raised to disconnect the coupling.

As the entire coupling is of such character 100 that it can be advantageously made of sheet metal, it follows that the cost of manufacture will be reduced, as castings are not necessary, and in addition there will be less danger of breakage in use. My invention is, 105 therefore, designed to solve many of the difficulties and problems involved in the coupling of an angle iron side rail to a wood corner post. With the construction, it will 110 be seen that the side rail can be turned over,

if it is desired to use transverse bed slats, as the vertical flanges of the angle iron rails will then extend upwardly to prevent end-wise displacement of the slats. In other words, the slots in the plates secured to the ends of the said rails will engage the hooks in either position of the side rails, and thus the latter can be used either with the ordinary bed bottom, such as those having a frame on which is stretched a metal fabric, or with ordinary slats. In the drawings, the horizontal flange 2 of the angle iron rail is shown in position to form the top of the rail, but when the members G and the rail are turned upside down, this flange 2 will then be at the bottom, and the vertical flange 1 will extend upward.

What I claim as my invention is:—

1. In a bed frame, a corner post, a bracket plate secured to said post, a side rail, and a coupling member on the end of said rail, said plate and member having devices whereby they are coupled together flatwise, said rail being of angle iron formation, one side wall 25 of said member being secured to the vertical web of said rail, and the other side wall having a portion thereof cut away and bent inward to rest on top of said rail, and said member being trough-shaped with the channel thereof extending vertically to contain said devices and receive the end of said rail.

2. In a bed frame, a corner post, a bracket plate secured to said post, a side rail, and a coupling member on the end of said rail, said plate and member having devices whereby they are coupled together flatwise, and said member having parallel vertical side walls which are secured to said rail, one side wall of said member being secured 40 to the vertical flange of said rail, and the other side wall having an inwardly bent portion secured to the horizontal flange of said rail.

3. In a bed frame, a corner post, a bracket plate secured to said post, a side rail, and a coupling member on the end of said rail, said plate and member having devices whereby they are coupled together flatwise, and said member having parallel vertical side walls which are secured to said rail, said rail being of angle iron formation, one side wall of said member being secured to 50 the vertical web of said rail, and the other

side wall having a portion thereof cut away and bent inward to rest on top of said rail. 55

4. In a bed frame, a corner post, a bracket plate secured to said post, a side rail, and a coupling member on the end of said rail, said plate and member having devices whereby they are coupled together flatwise, 60 said plate and member being of sheet metal, and said devices comprising opposite vertical edge portions of said plate cut away and bent outward to form hooks, disposed in vertical longitudinal planes and vertical 65 slots in said member to receive said hooks, which devices are arranged in pairs above and below said rail.

5. In a bed frame, a corner post, a bracket plate secured to said post, a side rail, and a coupling member on the end of said rail, 70 said plate and member having devices whereby they are coupled together flatwise, said rail having a top wall, and said member being trough shaped and having an inner horizontal web bent inward from one side wall and secured to said top wall. 75

6. A bedstead comprising corner posts, side rails, and a bracket plate and a coupling member for mounting the side rails 80 on said posts, said rails and the coupling members secured thereto being adapted for connection to the posts in different positions, one position causing one side of each rail to be uppermost, the other position 85 causing another side of said rail to be uppermost, and each rail being of angle iron formation, the horizontal flange of each rail serving as either the top or the bottom thereof, depending upon the position in 90 which the rail is coupled to the post, said plate and member having devices whereby they are coupled together flatwise, said plate and member being of sheet metal, and said devices comprising opposite edge portions 95 of said plate cut away and bent outward to form hooks, and slots in said member to receive said hooks, which devices are arranged in pairs above and below said rail.

Signed by me at Goshen, Indiana, this 100
2nd day of August 1915.
